UNITED STATES PATENT OFFICE.

ERNEST KEAST, OF NEGAUNEE, MICHIGAN.

EXCAVATING AND LOADING MACHINE.

1,422,767.

Specification of Letters Patent. Patented July 11, 1922.

Application filed January 24, 1921. Serial No. 439,569.

To all whom it may concern:

Be it known that I, ERNEST KEAST, a citizen of the United States, residing at Negaunee, in the county of Marquette and 5 State of Michigan, have invented certain new and useful Improvements in Excavating and Loading Machines; and I do declare the following to be a full, clear, and exact description of the invention, such as 10 will enable others skilled in the art to which it appertains to make and use the same.

This invention relates to an improved excavating and loading machine for use in mining, and one object of the invention is 15 to provide a machine of the character described so constructed that it may be used in digging a tunnel, the machine having a shovel for scooping up material at the end of the tunnel and delivering the material to 20 a car to the rear of the machine and upon the same track.

Another object of the invention is to so construct the machine that the carriage having the shovel pivotally connected therewith may be moved forwardly upon the truck of the machine or rearwardly, improved means being provided for swinging the scoop and scoop carrying arms vertically and dumping means being provided to 30 engage the scoop carrying arms and swing the arms and scoop back toward a lowered position after being emptied.

Another object of the invention is to so mount the carriage upon the truck that it 35 may swing horizontally thus permitting the scoop to engage material at the sides of the tunnel as well as directly in front of the machine.

Another object of the invention is to 40 provide improved air-actuated operating means for moving the excavating shovel longitudinally of the truck, checking means being provided to prevent this shovel from moving too rapidly.

Another object of the invention is to so 45 arrange the actuating and controlling means for the carriage that the valves of the air cylinder and oil cylinders may be simultaneously operated.

This invention is illustrated in the accompanying drawings, wherein:

Figure 1 is a top plan view of the improved machine.

Figure 2 is a view showing the machine 55 in rear elevation.

Figure 3 is a side elevation of the improved machine.

Figure 4 is a top plan view looking at the base plate of the carriage.

Figure 5 is a diagrammatic view of the controlling structure for the carriage.

This improved excavating and loading machine is adapted to move along the track rails 1 and is provided with a truck indicated in general by the numeral 2 and provided with axles 3 having wheels 4 for engaging the rails 1. This truck includes a plate or platform 5 having brackets 6 secured thereto and supporting pulley wheels 7 which are vertically disposed and positioned beneath the platform at the forward and rear ends of the truck. Cylinders 8 are mounted beneath the platform 5 at opposite sides of the truck and each is provided with a piston 9 which extends through the 75 head at the forward end of its cylinder. Cables 10 and 11 have been provided as shown, the cable 10 extending across the rear of the truck and having its end portions passed about the pulley wheels at 80 the rear end of the truck and then carried forwardly and connected with the pistons 9. The cables 11 are connected with the forward corner portions of the platform 5 and after being engaged with the pulley 85 wheels 14 at the forward ends of the pistons are engaged with the pulleys 7 and then connected with the tongue 12 which extends forwardly and downwardly from the base plate 13 of the carriage mounted upon the 90 truck. Suitable air pipes 15 have been provided so that compressed air may be admitted to the cylinders 8, it being understood that air will only be admitted to one cylinder at a time so that one piston may 95 be forced through its cylinder to draw upon the cables 11 and swing the base plate of the carriage to one side. The provision of the rear cables 10 will prevent the pistons from having movement independent of each 100 other and the cables 11 will thus at all times be kept tight and prevented from becoming slack.

The carriage is provided with side walls 16 which terminate in bearing bracket extensions 17 for rotatably mounting a roller 18. As previously explained, this carriage is pivotally connected with the truck by means of a pivot bolt or pin 19 so that if desired, the carriage may be swung upon 110

the truck to one side or the other, thus permitting the scoop 20 to remove dirt and rock from the side portions of a tunnel as well as from directly in front of the machine. This scoop 20 is carried by supporting arms 21 which extend rearwardly of the machine and have their rear end portions loosely mounted upon axles 22 which have mounted thereon, inner and outer 10 rollers or wheels 23 and 24. The inner rollers 23 rest upon the track bars 25 and the outer rollers or wheels 24 rest upon the angle-iron track bars 26 and beneath the guard strips 27. These guard strips 27 15 serve to prevent the outer rollers from leaving the track rails 26. The supporting arms 21 are to be swung upwardly and move the scoop from the filling position shown in full lines in Fig. 3 to the elevated or dumping position indicated by dotted lines in this 20 figure so that the earth and rock may be deposited in a suitable freight car or other similar car mounted upon the rails to the rear of the excavating and loading machine. 25 In addition to swinging upwardly, the scoop is to be moved forwardly and rearwardly, and in order to do so, there has been provided a pusher having side arms 28 which side arms are mounted upon the axles 22 and 30 have their outer end portions connected by a cross bar 29. These side arms 28 are provided with longitudinally extending upstanding side flanges 30 from which extend standards 31. These standards 31 have their 35 upper end portions 32 carried toward each other in converging relation as shown in Fig. 2 and terminate in upstanding ears which provide bearings 33 to rotatably mount the roller 34. A chest 35 is mounted upon the 40 platform 13 and this chest is provided with a longitudinally extending centrally disposed cylinder 36 and longitudinally extending cylinders 37 which are positioned upon opposite sides of the cylinder 36 and smaller 45 in diameter. The cylinder 36 is an air cylinder and the cylinders 37 are fluid cylinders to contain water, oil or any other suitable fluid. A relatively large piston 38 is mounted in the cylinder 36 and smaller pistons 39 50 are mounted in the cylinders 37, the pistons having close fit with the walls of the cylinders so that these pistons may move longitudinally through the cylinders but air and fluid may not pass the pistons. Piston 38 55 is provided with a piston rod 40 which extends through the forward end of the cylinder 36 and is connected with the cross bar 29 and the pistons 39 are provided with piston rods 41 which also extend through the forward 60 ends of their cylinders and have their forward end portions connected with the cross bar 29. From an inspection of the drawings, it will be readily seen that when the piston 38 which may be termed a driving 65 piston is moved through its cylinder, the

shovel or scoop may be moved longitudinally of the machine, the pistons 39 which may be termed braking or checking pistons serving to prevent the shovel or scoop from moving too rapidly.

It is desired to control movement of the pistons through their cylinders and in order to do so, the structure shown in Fig. 5 has been provided. Referring to this figure, it will be seen that there has been provided a 75 valve 42, the valve 42 being provided with an inlet neck 43 having engagement with a supply pipe 44 which pipe will lead from a suitable source of compressed air. An outlet neck 45 is provided for this valve 42 and side arms 46 and 47 have been provided for engagement with pipes 48 and 49 leading to and communicating with opposite end portions of the cylinder 36. The rotatable core 50 of this valve is provided with arcuate 80 passages 51 and 52 and from an inspection of this figure, it will be readily seen that when this core is rotated through the medium of the actuating lever or handle 53, the core may be moved from the closing position 85 to bring the passage 51 into communication with the inlet neck 43 and one of the side arms and at the same time, bring the passage 52 into engagement with the outlet 45 and the second side arm. Therefore, compressed air may be allowed to pass through one of the pipes 48 or 49 and into one end 90 of the cylinder 36 to move the piston 38 longitudinally through the cylinder, air being forced out of the cylinder through the second pipe and through the outlet of the valve. While the piston 38 is moving longitudinally, the pistons 39 will also move longitudinally in their cylinders and the oil, water or other liquid will be forced through outlets 100 at the ends of these cylinders and by means of pipes will be led to and will pass into the cylinders 41 at the opposite ends thereof. This piping mentioned consists of pipes 54 which are connected with the end portions 105 of one cylinder 41 and extend across the chest to the opposite side thereof where they are extended toward and connected with the opposite end portions of a valve 55. Branch pipes 56 are provided and connected 110 with the end portion of the second cylinder 37 and it will thus be seen that the pipes will have communication with the end portions of both of the cylinders 37. The core 57 of the valve 55 is provided with a passage 58 so that communication may be established between the two pipes 54 and the actuating handle or lever 59 of this valve 55 is engaged by a link 60 which is connected with a bell-crank lever 61, the bell-crank 61 being in its turn connected with a bell-crank lever 62 by means of a link 63. This bell-crank lever 62 is connected with the lever 53 by means of a link 64 and it will thus be 115 seen that when the lever 53 is moved to ad- 120 125 130

just the core of the valve 42, the core 57 of the valve 55 will also be moved and thus the two valves operated together. When the valve 42 is closed as shown in Fig. 5, the 5 valve 55 will also be closed and when the valve 42 is adjusted to establish communication between the pipe 44 and one of the pipes leading to one end of the cylinder 36 and provide communication between the 10 second pipe leading from the cylinder 36 and the outlet 45, the valve 55 will be opened thus permitting the fluid to pass from one of the pipes 54 to the second.

In order to permit the scoop to be swung 15 upwardly, there will be provided a suitable hoisting engine (not shown), the hoisting engine including a winding drum 65 upon which will be wound a cable 66. This cable 66 is passed over the rollers 18 and 34 and 20 is connected with the scoop so that when the cable is wound upon the drum, the scoop and arm 21 will be swung upwardly to the dotted line position of Fig. 3. In order to prevent the arms from swinging upwardly and striking 25 the roller 18, a violent blow, there have been provided checks in the form of rollers 67 rotatably mounted between arms 68 which are pivotally mounted by means of a shaft 69 which extends transversely across the 30 rear end portion of the machine. Springs 70 are connected with the side walls 16 and arms 68 so that the arms will be yieldably held against upward swinging movement. It will thus be seen that the springs will be 35 expanded when the rollers 67 are engaged by the arms 21 and therefore the arms 21 will be prevented from striking violently against the roller 18 and further that the springs 70 will tend to throw the arms 21 40 forwardly after the dirt and rock has passed out of the scoop. Therefore, the scoop will tend to return to a lowered position when the hoisting engine is reversed and the drum rotated to permit unwinding 45 of the cable.

When this device is in use, it will be moved along the track laid in the tunnel and brought to a stop adjacent the inner end of the tunnel where a pile of rock, dirt and 50 other similar material has been cut or blasted from the inner end portion of a tunnel being constructed. The lever 53 will be moved to open the valve 55 and admit air through the pipe 49 into the rear end portion of the 55 cylinder 36 and as this compressed air enters the cylinder, the piston 38 will be moved forwardly thus causing the shovel to be thrust forwardly as previously explained, the air in front of the piston passing out of the cylinder through the pipe 48 and out 60 through the outlet 45. As soon as the shovel has been filled, forward movement of the shovel will be discontinued by operation of the lever 53 and the shovel can then be 65 swung upwardly by operating the hoisting

engine to rotate the drum 65 and wind the cable 66 thereon. The air may be admitted to the forward end of the cylinder 36 to move the scoop carrier structure rearwardly as the cable is wound upon the drum or the 70 carriage may be first moved rearwardly and the drum then rotated to wind the cable and swing the arms upwardly. When the scoop or shovel reaches the position indicated by dotted lines, the rock or dirt will pass out 75 of the same and into a dirt car upon the track to the rear of the excavating machine. After the scoop is emptied, the drum may be released and the springs acting upon the arms 68 will swing the arms downwardly, 80 thus moving the arms 21 forwardly a sufficient amount for the weight of the shovel and arms to carry the arms downwardly. The rotation of the drum while unwinding will be controlled so that the scoop will 85 move easily to the lowered position. It will thus be seen that there has been provided an excavator which may operate upon a track having the dirt car to the rear of it and further that forward and rearward movement of the carriage will be controlled and the carriage prevented from moving forwardly and rearwardly beyond a desired speed by the fluid which must be forced out 90 of the cylinders 37 through one end and back into the cylinders through the opposite ends. It will be further noted that the carriage may be swung to one side by means of air admitted to the cylinders 8 so that rock and dirt may be removed from the side portions of the tunnel as well as directly in 95 front of the excavator. 100

I claim:

1. In a structure of the character described, a truck, a carriage mounted upon 105 said truck for transverse swinging movement, an arm extension at one end of said carriage intermediate its width, actuating means movable longitudinally of said truck and positioned adjacent the sides thereof, 110 guides carried by said truck, cables connected with said arm and engaging certain of said guides and slidably engaging said actuating means and secured to said truck, and a cable engaging other of said guides and having its end portions connected with said actuating means at the opposite ends thereof from said first mentioned cables. 115

2. In a structure of the character described, a truck, a carriage pivotally mounted upon said truck for transverse swinging movement, fluid cylinders carried by said truck and having piston rods sliding through their forward ends, guides carried by the side portions of said truck at the forward and 120 rear ends thereof, cables connected with the forward end portion of said carriage intermediate its width and engaged with the guides at the forward end of the truck and slidably engaging said piston rods and con- 130

5 nected with said truck, and a cable extending across the rear portion of said truck and engaging the guides at the rear end thereof and having its end portions extending into said cylinders and connected with the pistons of said piston rods.

3. An excavating machine comprising a carriage, tracks carried by said carriage, rollers movable along said tracks, axles for 10 said rollers, a scoop, carrying arms for said scoop extending rearwardly and loosely mounted upon said axles, a yoke having a cross bar and side arms loosely engaging said axles, means engaging the cross bar for 15 imparting longitudinal movement to said yoke, and means for swinging the scoop and carrying arms vertically.

4. An excavating machine comprising a body, a scoop, carriers movable longitudinally of said body, arms for said scoop pivoted to said carriers, a yoke having a cross bar and arms pivoted to said carriers, means for swinging said scoop vertically, means for returning the scoop towards a lowered 25 position, means connected with said cross bar for imparting longitudinal movement to said scoop, and means connected with said cross bar for controlling longitudinal movement of said scoop.

30 5. An excavating machine comprising a body, a scoop, carriers movable longitudinally of said body, arms for said scoop pivoted to said carriers for vertical swinging movement, a yoke having arms pivoted to 35 said carriers, standards carried by the arms of said yoke, a roller carried by said standards, a roller carried by said body, hoisting means including a drum and a cable wound upon said drum, and carried over said rollers and connected with said scoop, and means connected with said yoke for imparting longitudinal movement to the same.

40 6. An excavating machine comprising a carrier having a bottom and side walls 45 spaced upper and lower tracks carried by the side walls, inner tracks carried by the bottom in spaced relation to the lower tracks of the side walls, a scoop, arms carrying said scoop, rollers positioned between the 50 upper and lower tracks of the side walls and other rollers resting upon the inner tracks, axles carrying said rollers and having said arms loosely mounted thereon, a yoke having side arms engaging said axles, 55 means engaging said yoke for moving said scoop longitudinally, and means for swinging the scoop and scoop carrying arms vertically.

7. An excavating machine comprising a 60 body, carrier means movable longitudinally of said body, an implement having arms

connected with said carrier means for vertical swinging movement, and means for imparting longitudinal movement to the carrier means and implement and controlling 65 the speed thereof, said means comprising an air cylinder and a fluid cylinder, each having a piston therein and a piston rod extending from the piston through the end of the cylinder, a push bar carried by said piston 70 rods for engaging said implement, conduits having communication with opposite ends of said fluid cylinder and air cylinder, a valve for the conduit of the fluid cylinder, a valve for the conduit of the air cylinder having 75 an outlet and having communication with a feed pipe, and means for simultaneously adjusting said valves.

8. An excavating machine comprising a body, carriers movable longitudinally thereof, a scoop having arms connected with said carriers, a yoke connected with said carriers, an air cylinder, fluid cylinders, pistons in said cylinders having piston shafts connected with said yoke, a valve controlled conduit 80 having connections with opposite ends of said fluid cylinders, a valve controlled conduit having connections with opposite ends of the air cylinder, actuating means for the valve of each conduit, and means for imparting movement from the actuating means of one valve to the other.

9. An excavating machine comprising a body, carrier means carried by said body and movable longitudinally thereof, an implement having arms carried by said carrier means for vertical swinging movement, and means for imparting longitudinal movement to the carrier means and implement and controlling movement thereof, said means including cylinders having pistons movable therein, piston rods extending from the pistons through the ends of the cylinders, a push bar carried by the pistons for engaging the implement, conduits having their 105 end portions communicating with said cylinders, a valve connecting the end portions of one conduit and having an actuating lever handle, a valve for the second conduit connecting the end portions thereof and 110 having an inlet and an outlet, a plug for the last mentioned valve for selectively establishing communication between the inlet and one end portion of its conduit and the outlet and second end portion of the conduit, 115 a lever handle for said plug, and means connecting said lever handles for transmitting movement from the one to the other.

In testimony whereof I have hereunto set my hand.

ERNEST KEAST.
